STOP-MOTION MECHANISMS FOR
SEWING MACHINES

Ray D. Sweet, Bridgeport, and William J. Edwards, Stratford, Conn., assignors to The Singer Manufacturing Company, Elizabeth, N. J., a corporation of New Jersey

Application March 1, 1954, Serial No. 413,228

5 Claims. (Cl. 112—219)

The present invention relates to sewing machines and has for a primary object to provide a new and improved stop-motion mechanism for sewing machines.

More particularly, it is an object of the present invention to provide combined driving and stop-motion mechanisms for sewing machines similar to that disclosed and claimed in the co-pending application of Ivanko, Serial No. 385,097, filed October 9, 1953, now Patent No. 2,721,526, October 25, 1955, which mechanisms are provided with improved actuating means.

In addition, it is an object of this invention to provide, in a tacking machine having a stop-motion mechanism automatically actuated upon completion of the tack for bringing the machine to a stop, means for varying the number of stitches in the tack. Specifically, it is an object of this invention to provide means in such a machine for bringing the stop-motion mechanism into operation after only a fraction of the predetermined tack has been made or at an intermediate point in the designed tacking cycle and again at the end of the designed tacking cycle, thus producing two tacks each consisting of a fraction of the originally designed tack.

Having in mind the above and other objects that will be evident from an understanding of this disclosure, a presently preferred embodiment of the invention is hereinafter set forth in such detail as to enable those skilled in the art readily to understand the function, operation, construction and advantages of it when read in conjunction with the accompanying drawings, in which:

Fig. 1 is an elevation view of a sewing machine embodying the present invention, the cover-plate of the frame being removed and portion of the bed broken away and shown in section better to illustrate the invention.

Fig. 2 is a section view taken substantially on the line 2—2 of Fig. 1.

Fig. 3 is a fragmentary section view taken substantially on the line 3—3 of Fig. 2.

Fig. 4 is a view similar to Fig. 3 but showing the elements in a different operative position.

Fig. 5 is a fragmentary section view taken substantially on the line 5—5 of Fig. 1.

Fig. 6 is a fragmentary view in elevation of a detail of the mechanism as illustrated in Fig. 5.

The present invention is illustrated in the drawings as embodied in a tacking machine such as a button sewing machine having a frame including a bed 1, a standard 2 rising from one end of the bed, and a bracket-arm 3 overhanging the bed 1 and terminating in a head 4. The machine rests upon a base 5 and is pivotally mounted thereto along the lower rear edge of the bed 1 by a pair of pivots, one of which is illustrated in Fig. 5, the pivots comprising a pin 6 that extends through an apertured lug 7 carried by the base 5 and a pair of lugs 8 carried by the bed 1. The base 5 is provided with resilient feet 9 which are adapted to support the same upon any suitable supporting surface, such as a sewing machine table.

Journalled longitudinally of the bed 1 is a main-shaft

2

or bed-shaft 10 which extends through the side-wall of the machine-bed and has secured upon the external end thereof a belt-pulley, indicated generally by the numeral 11, which is formed of two separable parts as hereinafter 5 more fully explained, by means of which pulley power is delivered to the machine. The stitching mechanism of the machine comprises a needle-bar 12 mounted in the head 4 for vertical reciprocation, which needle-bar carries a needle 13 at its lower end, and a wing-type looper 14 10 mounted upon the end of a looper-shaft 15 which is journaled in a cylindrical work-supporting extension or arm 16 of the bed 1 and parallel to the bed-shaft 10. The looper-shaft 15 is designed to be operatively connected to the bed-shaft 10 to be rotated thereby at a one-to-one ratio. The needle-bar 12 is reciprocated by appropriate connections with an oscillating-arm-shaft 17 15 journalled longitudinally of the arm 3. The arm-shaft 17 is oscillated by means of a crank-arm 18 secured to the shaft and having the end thereof pivoted to the upper 20 end of a connecting-rod 19 arranged vertically in the standard 2 and connected at its lower end to a crank 20 formed on the bed-shaft 10. The needle-bar 12 is so mounted as to be capable of movement laterally of the arm 16 of the bed 1 and lateral vibration is imparted thereto by a lever 21 pivoted to the frame by an adjustable pivot 22 and oscillated by means of a cam groove (not shown) in a cam 23. The cam 23 is secured to a cam-shaft 24 journalled vertically in the standard 2, to which cam-shaft is secured a second cam 25. Rotation 25 is imparted to the cam-shaft 24 by a gear 26 fixed thereto and meshing with a worm (not shown) on the rotary bed-shaft 10. Means are provided for vibrating the looper 14 in timed relation with the vibration of the needle to maintain proper stitch-forming relation between them, which means, while not illustrated herein in detail since such constructions are old and well known, may be actuated by a cam follower 27 carried by an arm 28, which follower cooperates with a cam groove 29 (Fig. 5) in the upper face of the cam 25.

In the illustrated machine there is provided a button-clamp 30 having the usual button-clamping jaws 31, which button clamp is pivotally mounted by means of a horizontally arranged pivot pin 32 to a frame 33 slidable longitudinally of the bed 1. As is customary in button sewing machines adapted to sew four-hole buttons, the needle is vibrated laterally of the work-supporting arm between two of the holes in the button until the desired number of stitches therethrough have been made. The clamp is then shifted longitudinally of the arm and the needle is vibrated laterally of the arm between the other two holes in the button. To shift the frame 33 longitudinally of the arm 16 there is provided a shaft 34 (Fig. 5) journalled vertically in the bed 1 and oscillated by means of a crank-arm 35 fixed to the lower end thereof and carrying at its outer end a follower that cooperates with a cam groove (not shown) in the upper face of the cam 25. At its upper end the shaft 34 is operatively connected to the frame 33 for reciprocating the frame longitudinally of the work-supporting arm upon oscillation of the shaft, which connections are not herein described in detail since they form no part of the present invention. The button-clamp 30 is resiliently urged about its pivot 32 toward the slide-plate 36 forming a part of the frame 33 by a presser mechanism that includes a hollow presser-bar 37 55 that engages the button-clamp 30 at its lower end and is slidably mounted at its upper end in a bushing 38 carried by the bracket-arm 3. The presser-bar 37 is urged downwardly by a spring 39 fitted into the hollow bore of the presser-bar and abutting at its lower end with the bottom thereof and at its upper end against the end of an adjusting screw 40 threaded into the bushing 38. The button-clamp 30 may be raised and lowered by a longi-

tudinally adjustable link 41 connected at its lower end to the button-clamp and at its upper end to the end of a crank-arm 42 fixed to a clamp-lifter shaft 43 journaled longitudinally of the standard 3 parallel to the arm-shaft 17. The shaft 43 is oscillated by a rod 44 mounted vertically in the standard 2 for vertical sliding movement and connected at its upper end by a connecting link 45 to the end of a crank-arm 46 secured to the shaft 43. The rod 44 is urged downwardly, which is the direction in which the button-clamp 30 will be lowered, by a spring 47. The rod 44 may be raised to open the button-clamp 30 by exerting a pull on a chain 48, as by a conventional foot-treadle, which chain 48 extends through an aperture 49 in the base 5 (Fig. 5) and is connected to one arm 50 of a bell-crank lever that is pivoted to the base 5 by means of a pin 51 passing through the lever and lugs 52 upstanding from the base 5. The other arm 53 of the bell-crank lever underlies the lower end of the rod 44. A spring 54 is provided to bias the bell-crank lever in the direction in which the arm 53 is moved away from the end of the rod 44. When a pull is exerted upon the chain 48, the bell-crank lever is pivoted to lift the rod 44 which in turn oscillates the shaft 43 and lifts the button-clamp 30.

The driving and stop-motion mechanisms of the disclosed machine include a two-part separable pulley 11, as hereinbefore mentioned, about which pulley is entrained a driving belt 55 that is adapted to be operatively associated with any suitable source of power. The pulley 11 consists of a fast pulley element 56 and a loose pulley element 57. The inner or fast pulley element 56 consists of a web or flange 58 having an annular surface 59 forming a first belt-groove face and formed upon the outer face of the flange 58 adjacent the outer edge thereof. The flange 58 is integral with a sleeve 60 keyed to the shaft 10 by a pair of keys 61 and held against sliding movement lengthwise of the shaft in one direction by a split ring 62 fitted into a groove 63 in the shaft and in the other direction by a bushing 64. The outer or loose pulley element 57 consists of a web or flange 65 having a cylindrical surface 66 and an annular surface 67 which form the bottom wall and second side face respectively for the belt-groove. A sleeve 68 is formed integral with the flange 65 and a soft metal bearing sleeve 69 is press fitted therein. The bearing sleeve 69 is mounted on the shaft 10 for rotation and sliding relative thereto. The sliding movement of the loose pulley element longitudinally of the shaft 10 is limited by a split ring 70 fitted in a groove 71 formed in the end of the shaft 10. A cap 72 is fitted over the end of the shaft 10 and formed to engage the sleeve 68 of the loose pulley element 57 and to be frictionally held thereon. The cap 72 carries an anti-friction ball 73 that is adapted to be engaged by a spring arm 74 which, as hereinafter more fully explained, serves to slide the loose pulley element 57 toward the fast pulley element 56. When pressure is exerted on the anti-friction ball 73 by the spring arm 74, the loose pulley element is forced into operative relation with the fast pulley element, as illustrated in Fig. 4, in which relation the belt 55 is clamped between the belt-groove faces 59 and 67. Thus, the belt 55 is frictionally held against slipping relative to the fast pulley element 59 and will thereby drive the machine. When the pressure on the ball 73 by the spring arm 74 is relaxed, the loose pulley element is free to move axially away from the fast pulley element thereby separating the belt-groove faces 59 and 67. The split ring 70 is positioned on the shaft 30 so that the loose-pulley element 57 can move away from the fast pulley a distance great enough to space the belt-groove faces 59 and 67 apart a distance greater than the width of the belt 55. There is provided a belt-shifter 75 (Fig. 1) carried by a bracket 76 secured to the frame and including an arm 77 adjustably carried by the bracket 76. An anti-friction roller 78 is mounted upon the end of the arm 77 and is arranged to be in continual rolling

contact with the belt upon that side opposite from the loose-pulley element. As the loose-pulley element 57 is moved toward the fast pulley element 56 it forces the belt 55 not only against the belt-groove face 59 but also against the roller 78 which slightly deforms the belt as at 79, which deformation is illustrated in exaggeration in Fig. 4. Thus, when the pressure on the loose-pulley element is relaxed the roller 78 will force the belt and consequently the loose-pulley element away from the fast pulley element, thereby moving the belt away from driving relation with the fast pulley element. The belt will then ride on the bottom wall 66 of the loose-pulley element which will rotate idly on the shaft 10.

The stop-motion mechanism comprises a face-cam 80 formed as an integral portion of the flange 58 of the fast pulley element 56. The cam 80 includes a recess 81 including a stop-shoulder 82, as best seen in Fig. 4. A stop-arm 83 formed to be seated in the recess 81 includes a strap portion 84 that loosely encircles the sleeve 60 of the fast pulley element. The stop-arm 83 is carried by a lever 85 which at its lower end is provided with a strap-portion 86 encircling a lateral enlargement of the strap-portion 84 of the stop-arm and held thereon by a split-ring 87 fitted in a groove in the strap-portion 84 of the stop-arm. At its upper end, the lever 85 is pivoted by means of a pivot pin 88 to a bracket 89 that is secured to the standard 2 by screws 90.

The free end of the stop-arm 83 is pivoted by means of a pivot pin 91 to a yoke 92 upon the lower end of a resiliently-centered stop-rod 93. The stop-rod 93 slidably extends through a center-block 94 that is fixed to an arm 95 integral with the lever 85 and extending laterally therefrom. A pair of coiled compression springs 96 and 97 encircle the stop-rod 93, the spring 96 acting between the center-block 94 and the yoke 92 and the spring 97 acting between the center-block 94 and a washer 98 held upon the upper end of the stop-rod 93 by a pair of nuts 99. It will be apparent that with the stop-motion mechanism thrown into operative relation with the stop-cam 80 by pivoting the lever 85 about its pivot pin 88, the stop-arm 83 will be in sliding engagement with the face of the cam 80 until the recess 81 comes around. The stop-arm 83 will then be engaged by the stop-shoulder 82 and will fall into the recess 81, thus stopping the machine. The momentum of the moving parts of the machine will be initially absorbed in the spring 97 which resists the depression of the stop-rod 93. The rebound in the spring 97 will act against the spring 96, which springs thus resiliently center the stop-rod 93.

The spring arm 74, which is the actuating element for sliding the loose-pulley element axially of the shaft 10, is fixed at its lower end, as by screws 100, to the bracket 76. The spring-arm 74 is arranged to engage the anti-friction ball 73 at a point intermediate its ends and the upper end thereof is located between opposed knife-edges 101 (see Fig. 1) formed in a block 102 carried at the end of a rod 103 that is, in turn, carried by the arm 95. As the lever 85 is moved about its pivot 88, the rod 103 through the knife-edges 101, will flex the spring-arm 74 toward or away from the anti-friction ball 73 carried by the loose-pulley element 57. When the spring arm 74 is flexed toward the ball 73, it resiliently urges the loose-pulley element 57 toward the fast pulley element 56. It will be apparent that because of the resiliency of the spring-arm 74 and the leverage of the system, the amount of motion imparted to the upper or loose end of the same by the block 102 in order to obtain a predetermined motion of the loose-pulley element 57 toward the fast pulley element, or to secure a predetermined pressure between the belt 55 and the opposed belt-groove faces 59 and 67, is not critical as would be the case if rigid linkages were employed.

As hereinabove pointed out, as the lever 85 is moved about its pivot 88 clockwise as seen in Fig. 1, the loose-pulley element 57 is moved toward the fast pulley element 56 to clutch the belt 55 to the fast pulley element, and

at the same time, the stop-arm 83 of the stop-motion mechanism is moved out of the recess 81 in the stop-cam 80 and out of operative relation with the stop-cam. When the lever 85 is moved counterclockwise as seen in Fig. 1, the belt 55 is unclutched from the face 59 of the fast pulley element, and the stop-arm 83 is moved into engagement with the cam-face of cam 80 and as the recess 81 comes around, the stop-arm will contact the stop-shoulder 82 and fall into the recess 81 to stop the machine. Means are provided for swinging the lever 85 about its pivot, which means includes an arm 104 secured to the arm 95 of the lever 85 by screws 105 and extending to the interior of the standard 2. To the end of the arm 104 there is pivotally connected a link 106 which is also pivotally connected to a rod 107 disposed vertically within the standard 2 for longitudinal sliding movements. A spring 108 is coiled about the rod 107 and held in compression between a bushing 109 formed in the standard and through which bushing the rod 107 slidably extends, and a collar 110 fixed to the rod 107 by a set-screw 111. The collar 110 is formed to provide vertically stepped shoulders 112 and 113 which are designed to cooperate successively with the end 114 of one arm 115 of a bell-crank lever 116, which arm thus holds the rod 107 elevated against the action of spring 108 in either one of two positions. The bell-crank lever 116 is fixed to a rod 117 that is arranged transversely of the bed 1 and pivotally mounted in the side walls thereof. A cam-plate 118 is adjustably fixed to the periphery of the cam 25 by set-screws 119 that extend through slots 120 in the cam-plate and are threaded into the cam 25, which cam-plate is designed to contact and thereby pivot the other arm 121 of the bell-crank lever 116. The cam-plate 119 includes a first cam surface 122 and a second cam surface 123. The cam surface 122 is so designed that when the arm 121 of the bell-crank lever is depressed thereby, the other arm 115 of the lever will be pivoted only enough to move the end 114 thereof from under the shoulder 113 of the collar 110 but not enough to move it from under the shoulder 112, so that the rod 107 will move down under the action of spring 108 only for the vertical distance between the shoulders 112 and 113. The second cam surface 123 is designed to depress the lever arm 121 enough to cause the end 114 of the other lever arm 115 to move from under the shoulder 112 of the collar 110 and thus release the rod 107 for movement downwardly to its end position under the action of spring 108.

As will be evident, downward movement of the rod 107 will pivot the lever 85 counterclockwise to declutch the driving belt 55 and to move the stop mechanism into operation. The downward movement of the rod 107 for the distance between the shoulders 112 and 113 is designed to release the loose-pulley element 57 for movement away from the fast pulley element 56 for a distance great enough to declutch the belt 55 from the fast pulley element 56, but not enough to bring the stop mechanism into operation. Thus, while the arm 121 rides on the cam-surface 122 the machine will continue to operate but will be disconnected from the drive means and thus coasting. The length of the cam-surface 122 may be varied but in the disclosed machine it is designed to represent two complete stitching cycles. When the arm 121 is raised onto the cam-surface 123, the rod 107 will move downwardly enough to bring the stop-motion mechanism into operation. It will also be evident that when the rod 107 is raised against the action of spring 108, the lever 85 will be swung to retract the stop-motion mechanism and to clutch the driving belt 55 to the fast pulley element 56. A coil tension spring 124 is connected at one end to the arm 115 of the bell-crank lever 116 and at the other end to the frame to bias the lever 116 so that when the rod 107 is raised, the end 114 will move under the shoulders 112 and 113 to hold the rod in raised position. To facilitate raising the rod 107 there is provided a bell-crank lever 125 pivoted to the base 5 by a pivot pin 126 and having a first arm 127 connected by means of a chain 128 that

extends through an aperture 129 in the base 5 to a foot treadle (not shown) or other suitable means for exerting a pull on the chain 128 and having a second arm 130 carrying a roller 131 at its free end that underlies the end of the rod 107. A spring 132 is provided for biasing the bell-crank lever 125 about its pivot with the arm 130 down.

The illustrated machine is designed to produce a 16-stitch tack for securing four-hole buttons to a garment in the customary manner. Consequently, the cam 25 is geared to make one complete revolution in 16 stitches or in 16 revolutions of the bed-shaft 10 and at the end of the tacking cycle, the stop-motion mechanism is brought into operation to bring the machine to a stop. In addition to producing 16-stitch tacks, the present machine is provided with means for bringing the stop-motion mechanism into operation half-way through the stitching cycle, thus producing an 8-stitch tack upon each actuation of the machine as in sewing two-hole buttons to a garment, and producing two 8-stitch tacks upon each revolution of the cam 25. Towards this end the bell-crank lever 116 is fixed by means of a pin 133 to the rod 117, which rod is disposed transversely of the bed 1 and pivotally mounted in the walls thereof. The mounting for the rod 117 consists of a pivot pin 134 rotatably mounted in a side wall of the bed 1 and having a reduced end portion 135 threaded into the end of the rod 117. The rod 117 is held against axial sliding movement by the head 136 of the pin 134, the side wall of the bed 1 being held between head 136 and the end of the rod 117. At its opposite end, the rod 117 is mounted in a sleeve 137 for rotation and sliding relative thereto which sleeve is in turn carried by a side wall of the bed 1 for rotation and sliding relative to the bed 1.

35 The one end 138 of the rod 117 adjacent the sleeve 137 is slabbed off to form opposed parallel sides. A lever 139 having a hub 140 provided with a transverse aperture corresponding to the cross-section of the end 138 of the rod 117, is mounted on the rod 117 for sliding movement longitudinally thereof and held against rotation relative to the rod by the key-effect of the cross-section of the end 138 of the rod. A spring 141 is coiled about the rod 117 and held in compression between the hub 140 of the lever 139 and a collar 142 fixed to the rod, which thus urges the lever 139 into engagement with the end of the sleeve 137 and consequently urges the sleeve 137 outwardly or off the end of the rod 117. At its outer end the sleeve 137 is provided with an arm 143 having a finger piece 144 upon the end thereof to facilitate rotating the same, which arm is designed to cooperate with a plate 145 to limit sliding movement of the sleeve 137 relative to the rod 117. The plate 145, which is secured to the side wall of the bed 1 by screws 146, is semi-circular and at the hub thereof is provided with an aperture 147 that receives the rod 117. A segmental slot 148 having end-walls 149 that are arranged radially of the plate 145 is formed on the inner face of the plate and is designed to receive the arm 143. The inner face of the plate 145 within the area of the segmental slot 148 is provided with a face-cam 150 that presents two rest-points 151 and 152, one adjacent each of the end-walls 149 of the slot, which rest-points are spaced axially of the rod 117.

65 It will be apparent that as the arm 143 is rotated relative to the rod 117 and relative to the plate 145, from a position on the rest-point 151 to a position on the rest-point 152, the sleeve 137 will be moved axially of the rod 117 against the spring 141 by the cam face 150, which movement of the sleeve 137 is imparted to the hub 140 of the lever 139. The lever 139, which is normally out of the path of travel of the cam-plate 118 on the periphery of the cam 25, as illustrated in Fig. 5, will thus be moved into operative relation with the same. When the cam-plate 118 is rotated around, it will cooperate with the lever 139 in the same manner as it cooperates with the

arm 121 of the bell-crank lever 116. Since the lever 139 is keyed to the rod 117 by the slabbed-off cross-section of the end 138, the moving of the end of the lever 139 by the cam-plate 118 will rotate the rod 117 and thus the bell-crank lever 116 which is also fixed to the rod 117 against rotation relative thereto. Thus, since the bell-crank lever 116 is pivoted in the same manner as if it had been actuated by the cam-plate 118, the stop-motion mechanism is also actuated in the same manner as hereinbefore described with relation to the bell-crank lever 116. Thus, the stop-motion mechanism will be actuated upon each half of a revolution of the cam 25, which in the illustrated machine is at the end of eight stitches. When the arm 143 is rotated from the rest-point 152 to the rest-point 151, the lever 139 is moved by the spring 141 out of the path of travel of the cam-plate 118, and the stop-motion mechanism will be brought into the operation only after a complete revolution of the cam 25, which in the illustrated machine represents sixteen stitches. The end walls 149 of the slot 148 are so positioned that when the stop-arm 143 is swung into contact with the same, it will be on one of the rest points 151 or 152 respectively.

Having thus set forth the nature of the invention, what we claim herein is:

1. In a sewing machine having a frame, a rotary shaft journaled in said frame, a belt-pulley having a fast pulley element fixed to said shaft and a complemental loose pulley element mounted upon said shaft for rotation and translation relative thereto, a lever pivoted to the frame on an axis in a plane normal to said shaft, a rod mounted in said frame for axial sliding movement and arranged in a plane normal to said shaft, operative connections between said rod and said lever to pivot the latter upon sliding movement of said rod, a spring for urging said rod in one direction, manual means for moving said rod in the other direction, a collar on said rod, said collar having a pair of stepped shoulders, a pivoted lever-arm adapted to cooperate with said shoulders individually to hold said rod against the action of said spring in a selected one of two positions, said lever arm being adapted to be swung successively from a position in cooperation with one of said shoulders, to a position in cooperation with the other of said shoulders, and to a position in which it is out of cooperation with both of said shoulders, means responsive to a predetermined number of revolutions of said rotary shaft for swinging said lever to its successive positions, stop-motion mechanism comprising a stop-shoulder carried by said fast pulley element and a resiliently-centered stop-arm carried by said lever and adapted to cooperate with said stop-shoulder to stop rotation of said shaft, said stop-arm being in cooperative relation with said stop-shoulder only when said shoulders on said rod are released by said lever-arm for movement of said rod under the action of said spring to swing said lever, and means for moving said loose pulley element toward driving relation with said fast pulley element in which a driving belt is frictionally clamped to said fast pulley element, said means comprising a leaf spring fixed at one end to said frame, at the other end operatively connected to said lever to be flexed thereby upon swinging movement of said lever, and at an intermediate portion engaging said loose pulley element to slide the same axially of the shaft upon flexing of said leaf spring, said loose pulley element being in driving relation with said fast pulley element under the action of said leaf spring only when said lever-arm is in cooperation with that one of said stepped shoulders which is adapted to hold said rod in the maximum position in the direction against the action of said spring.

2. In a sewing machine having a frame, a rotary shaft journaled in said frame, driving means for delivering power to said shaft comprising a belt-pulley and clutching means for coupling a driving belt in driving relation

to said belt-pulley, stop-motion mechanism for stopping rotation of said shaft, manually-operated means for coupling said belt in driving relation to said belt-pulley and simultaneously releasing said stop-motion mechanism to permit rotation of said shaft, means responsive to a predetermined number of revolutions of said shaft for uncoupling the driving belt from said belt-pulley and for actuating said stop-motion mechanism to stop rotation of said shaft, said last-mentioned means including a rotary actuating element, operative connections between said actuating element and shaft for driving the element at a predetermined ratio with respect to the rotation of said shaft, a first member arranged in cooperative relation with said actuating element and a second member arranged to be moved selectively into and out of cooperative relation with said actuating element at a point spaced angularly relative to said actuating element from said first member, whereby said driving means may be uncoupled from said shaft and said stop-motion mechanism will be actuated to stop rotation of said shaft at the completion of a cycle of rotation of said rotary actuating element and selectively at an intermediate point in the cycle.

3. In a sewing machine having a frame, a rotary shaft journaled in said frame, stop-motion mechanism for stopping rotation of said shaft, and means responsive to a predetermined number of revolutions of said shaft for actuating said stop-motion mechanism, said means comprising a rotary cam journaled in said frame, operative connections between said rotary shaft and said cam for driving the latter at a predetermined ratio with respect to the rotation of the shaft, a rod pivotally mounted in said frame, a first lever-arm fixed to said rod and arranged to cooperate with said cam to be pivoted thereby in one direction about the pivot-axis of said rod and thereby pivot said rod, means for biasing said first lever-arm in the other direction about the pivot-axis of said rod, operative connections between said rod and said stop-motion mechanism to actuate the latter upon pivotal movement of said rod, a second lever-arm mounted on said shaft for axial sliding relative thereto and keyed to said shaft for pivotal movement therewith, said second lever-arm being arranged to cooperate with said cam at a point angularly spaced with respect to the axis of said cam from said first lever-arm, and manual means for selectively moving said second lever-arm into and out of cooperative relation with said cam.

4. In a sewing machine having a frame, a rotary shaft journaled in said frame, stitching mechanism operated by said shaft and defining a point of stitch-formation, a work-clamp, means for jogging said work-clamp relative to the point of stitch-formation comprising a cam-shaft journaled in said frame, operative connections between said rotary shaft and said cam-shaft for rotating the latter upon rotation of the rotary shaft at a predetermined ratio to the rotation of the rotary shaft, a cam fixed to said cam-shaft and operative connections between said cam and said work-clamp for jogging the latter through a predetermined stitching cycle upon each revolution of the cam-shaft, stop-motion mechanism for stopping rotation of said rotary shaft and means for actuating said stop-motion mechanism upon completion of each stitching cycle comprising a cam-surface on said cam, a rod pivotally mounted transversely of said frame, a first member fixed to said rod and arranged to cooperate with said cam-surface to pivot said rod, and operative connections between said rod and said stop-motion mechanism to actuate the latter upon pivotal movement of said rod, and means for selectively actuating said stop-motion mechanism at an intermediate point in the stitching cycle comprising a second member mounted on said rod for axial sliding movement and keyed to said rod for pivotal movement therewith, said second member being arranged in operative relation with said cam-surface, and manual means for moving said second member into and out of operative relation with said cam-surface.

5. In a sewing machine having a frame, a rotary shaft journaled in said frame, drive means for said shaft including clutch means for selectively coupling and uncoupling a drive belt in driving relation to said shaft, stop-motion mechanism including a stop-shoulder associated with said shaft for unitary rotation and a resiliently centered stop-arm movable into and out of cooperation with said stop-shoulder and adapted when in cooperation with said stop-shoulder to stop rotation of said shaft, a lever pivoted to said frame on an axis in a plane normal to said shaft, operative connections between said lever and said clutch means and stop-motion mechanism for successively uncoupling said clutch means and actuating said stop-motion mechanism upon continued motion of said lever, a rod mounted in said frame for axial sliding movement and arranged in a plane normal to said shaft, operative connections between said rod and said lever for pivoting said lever upon axial sliding movement of said rod, a spring for urging said rod in the direction to uncouple said clutch means and actuate said stop-motion mechanism and manual means for moving said rod in the other direction, a collar on said rod, said collar having a pair of shoulders spaced longitudinally of said rod, a pivoted lever arm cooperating individually with said shoulders to hold said rod against the action of said spring, said lever arm being swingable successively from a position in cooperation with

the first of said shoulders to a position in cooperation with the second of said shoulders and then to a position in which it is out of cooperation with both of said shoulders, said shoulders being disposed along said shaft so that 5 when said lever-arm is in cooperation with said first shoulder said clutch means is coupled to said shaft and said stop motion mechanism is out of operation when said lever-arm is in cooperation with the second of said shoulders, said clutch means is uncoupled from said shaft and 10 said stop-motion mechanism is out of operation, and when said lever-arm moves out of cooperation with the second of said shoulders said stop-motion mechanism will be actuated, and means responsive to a predetermined number of revolutions of said rotary shaft for swinging said lever to 15 its successive positions.
